UNITED STATES PATENT OFFICE.

DAVID L. BARNUM, OF WILSON, NEW YORK.

THILL-CULTIVATOR.

SPECIFICATION forming part of Letters Patent No. 269,376, dated December 19, 1882.

Application filed September 21, 1882. (No model.)

To all whom it may concern:

Be it known that I, DAVID L. BARNUM, a citizen of the United States, residing at Wilson, in the county of Niagara and State of New York, have invented certain new and useful Improvements in Thill-Cultivators; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

15 This invention relates to certain new and useful improvements in one-horse thill-cultivators; and it consists in the peculiar construction and arrangement of parts, as will be hereinafter more fully described.

20 In the annexed drawings, Figure 1 is a side view of my improved cultivator. Fig. 2 is a plan and Fig. 3 is an end view of the same.

The machine consists of a wooden frame of side bars and cross-bars. The side frames, A A, and front cross-bar, A', are secured together and made rigid by means of iron angle-plates or castings C, which fit on their under sides, where they come together and are bolted to said side pieces and bar, as shown in dotted lines in Fig. 2. To the outer sides of the side bars, A A, are bolted the thills B B.

25 D D represent the usual handles for guiding the machine, which are pivoted to the side bars at the front of the cultivator at the points a a. Slotted castings or uprights E E are bolted to the side bars, A A, at the rear of the machine. By means of the bolts or lugs b b on the handles D D, which fit in the slots in the uprights E E, the handles can be raised or lowered, as desired.

30 The device has three plows, one of which is behind and in a line passing between the forward and outer ones. The plow-standards F F are secured to the main frame by means of rods c c, extending from and through the standards to and through the front cross-bar, A', and bolted thereto, and rods or eyebolts d d, which pass up through the standards and

through slots in the cross-piece A², and are secured to the same by nuts, as shown in Fig. 50 2. The rear plow-standard, F', is likewise secured to a projecting piece or beam, A³, which is bolted to the cross-piece A² and to the front cross-bar, A', by means of rods c' and d', as shown. The rods d d' have eyes or loops at 55 their ends which fit around the rods c c' at the points where they meet and are bolted to the standards F F'. The slotted cross-piece A² rests on and is secured to two cross-bars, A⁴, which are bolted to the under sides of the side 60 bars, A A.

To the lower ends of the plow-standards are fastened castings, to which are secured the steel teeth or shovels f f'. By reversing the shovels the cultivator may be made to throw 65 in or out, as desired. (See Fig. 3.)

The plow-standards F F are adjustable on the cross-piece A² by means of the slots therein, thus permitting them to be placed nearer or farther apart, as desired.

70 Bolt-holes e e are so arranged in the side frames, A A, that the thills B B may be continued on a straight line with the sides or thrown upward, as shown in dotted lines in Fig. 1, thus regulating the pitch of the cultivator, as well as adapting it to the size or height of the horse.

A draw-hook, g, is attached to the under side of the front cross-bar, A', for attachment of a single-tree.

80 Having thus described my invention, what I claim as new, and desire to secure by Letters Patent, is—

In a thill-cultivator, the combination of the side pieces, A, cross-pieces A' A² A⁴, adjustable thills B, rearward-projecting piece A³, adjustable plow-standards F F, stationary plow-standard F', and bolts d d', all constructed and combined as and for the purpose described.

85 In testimony whereof I affix my signature in 90 presence of two witnesses.

DAVID L. BARNUM.

Witnesses:

EDWARD F. TURK,
D. CLINTON BARNUM.
